BANJO MUTE

Application filed June 6, 1929. Serial No. 368,795.

This invention relates to a mute attachment for a banjo which is adapted to mute the tone of the instrument simply by changing the position thereof and without it being necessary for the musician to alter the position of his hands while playing the instrument.

An object of the invention is to provide a device of this character which is an improvement upon other devices of its class with respect to simplicity of construction and dependability of operation, and which at the same time may readily be attached to banjos already on the market.

A further object of the invention is to provide a device which will either diminish the tone of the banjo or completely mute it, at the will of the musician, the extent to which the sound is deadened depending upon the angle to which the banjo is tilted.

Other objects and advantages may herein-after appear.

Referring to the accompanying drawings, which illustrate what is at present deemed to be a preferred embodiment of the invention,

Fig. 1 is an end elevation of the device, the position of the membrane or head of the banjo wherein the device is mounted being indicated by dotted lines.

Fig. 2 is a side elevation looking at Fig. 1 from right to left, the membrane of the banjo being omitted.

Fig. 3 is a cross sectional detail on line 3—3 of Fig. 1.

Fig. 4 is a cross sectional detail on line 4—4 of Fig. 2.

Fig. 5 is a section on line 5—5 of Fig. 3.

Fig. 6 is a back view of a complete banjo showing the device mounted therein.

Referring in detail to the drawings, the device comprises a frame or base 7 which is supported within the banjo head 8 by means of the pair of rods 9 which form a part of the banjo.

Said base 7 is securely clamped to and between said rods 9 by means of a clamping device comprising a follower 14, screw bolt 15, sleeve 16 and thumb nut 17. Said clamping device also comprises a spacing element 18 which is provided at each end of the fol-

lower 14 with a pair of guiding lugs or ears 19.

From one side of base 7 extends an arm to the outer or upper end of which, as viewed in the drawings, is pivotally secured by a pivot bolt 25, a pendulum 26 which carries at its free end a counter weight 27.

Said pendulum 26 is provided with a guide plate 28 held against spacing sleeves 29 by means of screws 30 which are screwed into a bracket 31 attached to the recited arm 9.

Said pendulum 26 has attached thereto an arm 35 which operates the mute proper as will be described later. Said arm 35 is desirably a flat metal strip which is secured to the pendulum 26 by screws 26^a and 26^b and which is provided throughout its projecting portion with a part 36 which, by a twist 37 is disposed at a right angle to the part thereof which is attached to the pendulum 26.

The arm 36 is adjustable in order to control its action upon the parts with which it cooperates. For this purpose the screw or rivet 26^b acts as a pivot, the screw 26^a is threaded into the arm, and an adjusting slot 26^c is provided in the pendulum, said screw 26^a extending loosely through said slot and when screwed down serving as a clamp to hold the arm 36 in the desired position.

Adjustably secured to the upper face of the base 7 is an angular clip 40 the upper end of which carries an elongated bearing 41 which supports an oscillatory shaft 42, one end of said shaft projecting beyond said bearing and being there provided with an angularity projecting operating arm 43, the outer end of said arm being preferably provided with an antifriction sleeve 44 where it is engaged by the mute operating arm 35.

The adjustability of said clip 40 is afforded by providing in the base portion thereof slots 40^a through which loosely extend the screws 40^b which are screwed into the base 7.

The oscillatory shaft 42 also has fixed thereto means for supporting the mute proper 45.

Such supporting means comprise the supporting arm 46 which carries at its free end the pivot arm 47 which in turn pivotally supports mute disk 45 by means of the mute bracket 48.

The return movement of the mute proper is accomplished by means of the tension coil spring 50. Said coil spring 50 may be anchored at one end to the base 7 by means of a clip 51 and at its other end is attached to arm 46.

When, by varying the position of the banjo, the base 7 and the parts carried thereby are moved with relation to the pendulum, the 10 arm 35 of said pendulum will act upon the arm 43 and will oscillate the shaft 42 thereby swinging the mute proper 45 against the banjo membrane 55 indicated by dotted lines in Fig. 1. Owing to the mute proper 45 being pivotally mounted upon its supporting shaft 47 it will readily adjust itself so that its entire face portion will press against the banjo membrane 55. A weak leaf spring 60 is provided to hold the mute proper 45 parallel to the banjo membrane 55, when said mute proper is in its retracted position, thus insuring that no portion of said mute proper will touch the membrane of the banjo at such times. Said leaf spring 60 is shown secured 20 to a screw 61 which is attached to the outer end of shaft 42.

The action of said spring 60 upon the mute proper will be understood best by reference to Fig. 5 where the position of the mute proper with relation to the arm 46 is that position which these parts occupy with relation to each other when the arm 46 is in its fully retracted position, or else the lower edge 30 of the mute as seen in Fig. 5 is just beginning to contact with the surface of the banjo membrane. When, after such contact has begun, the arm 46 has been swung farther upon its shaft 61 toward the membrane of the banjo, the mute proper 45 will rock upon 40 its pivot 47 until all portions of its face contact with the membrane of the banjo. The face of the mute proper is preferably provided with a cork layer 45^a which is secured to a metal plate.

45 The operation of the device need not be further described except to state that if the banjo drum is not tilted sufficiently to bring the entire face portion of the mute proper into contact with the banjo membrane, then 50 only a partial muting of the sound will take place. Hence the musician may either merely diminish the tone of the banjo or completely mute it, at will, the extent to which the sound is deadened depending upon the 55 angle to which the banjo is tilted.

By oscillating the banjo while the instrument is being played and at the same time is being held in such a position that the mute proper is only in approximate contact with the banjo membrane, a relative oscillation is produced between the pendulum and the parts operatively connected therewith, thus causing the mute proper to repeatedly engage and disengage the banjo membrane thereby 60 producing a vibrato tone effect.

It will be observed that the pivot 25 of pendulum 26 is located relatively near one side of the banjo head while the pendulum weight 27 swings close to the diametrically opposite side thereof, and the operating arm 70 35 carried by said pendulum to operate the mute is located between the pendulum weight 27 and the pivoted end of the pendulum. This construction makes it possible to use a 75 relatively long pendulum adapted to aid the musician in making more accurate adjustments of the mute.

Claims:

1. In a device of the character described, a frame, means to support said frame within a banjo in fixed relation thereto, a pendulum mounted on said frame, a movable mute mounted on said frame to swing at right angles to the plane in which said pendulum swings, means to transmit a swinging movement from said pendulum to said mute to bring said mute into contact with the membrane of the banjo, and means operable by a manual movement of the instrument to retract said mute from the position wherein it engages the membrane of the banjo.

2. In a device of the character described, a frame, means to support said frame within a banjo in fixed relation thereto, a pendulum mounted on said frame, a mute supporting frame mounted on the first recited frame to swing in a plane at right angles to the plane in which said pendulum swings, a mute carried by said mute supporting frame, an arm carried by said pendulum to swing said mute supporting frame to bring said mute into contact with the membranes of the banjo, and means operable by a manual movement of the instrument to retract said mute and its frame.

3. In a device of the character described, in combination, a banjo body and its membrane, a gravity operable plate to mute said membrane, means normally to support said plate spaced away from and parallel to said membrane, said supporting means comprising means to pivotally support said plate, means to swing said plate supporting means toward the banjo membrane to cause an edge portion of said plate first to come into contact with said membrane and then the entire face of said plate to contact therewith, and a spring to restore said plate to parallelism with said membrane upon its complete withdrawal from contact therewith.

4. In a device of the character described, in combination, a banjo body and its membrane, a support mounted within said body, a plate mounted upon said support, said plate being bodily movable to and from a position in which its face portion contacts with said membrane and being also tiltable about an axis extending transversely thereof, swinging gravity controlled means to move said plate into and out of contact with

said membrane, and a spring to restore said plate to parallelism with said membrane when said swinging means is in the retracted position.

5. In a device of the character described, in combination with the head and membrane of a banjo, a mute, means within the head to support the mute in operative relation to the membrane, a pendulum pivotally supported within the head, the point of pivotal support being located at one side of the axial center of the head, said pendulum having a weighted portion swingable thru a path located on the diametrically opposite side 10 of the point of pivotal support, and means carried by the pendulum intermediate its weighted portion and point of pivotal support to operate the mute.

6. In a device of the character described, 20 in combination with the head and membrane of a banjo, a mute, means within the head to support the mute in operative relation to the membrane, a pendulum pivotally supported within the head, the opposite end of 25 the pendulum characterized by a weighted portion, and means carried by the pendulum intermediate its weighted portion and point of pivotal support to slidably engage the mute supporting means to operate the mute.

30 In testimony whereof we hereby affix our signatures.
